Philemon O. Dickinson

UNITED STATES PATENT OFFICE.

PHILEMON O. DICKINSON, OF NEWARK, NEW JERSEY.

DESIGN FOR A BACK FOR BRUSHES, &c.

SPECIFICATION forming part of Design No. 24,982, dated December 17, 1895.

Application filed November 14, 1895. Serial No. 568,976. Term of patent 3½ years.

To all whom it may concern:

Be it known that I, PHILEMON O. DICKINSON, a citizen of the United States, residing at Newark, in the county of Essex and State of New Jersey, have invented and produced a new and original Design for Backs for Brushes and Similar Articles, of which the following is a description, reference being had to the accompanying drawing, which illustrates the design.

The general outline of the back is that of an extended or lengthened ellipse. Just within the outline edge is a border A of conventionalized rococo order, which border in varying form extends around the edge of the back.

Near each end of the back is the rococo flower-design B, passing from the border on one side to the border on the other side and forming the disks C C, as well as the central plaque D, of plain surface.

The essential features of the design are those above recited.

What is claimed as new is—

The herein described design for backs of brushes and similar articles, substantially as set forth.

PHILEMON O. DICKINSON.
